UNITED STATES PATENT OFFICE.

CHRISTIAN J. JENSEN, OF PRESTON, IDAHO.

BEET-TOPPING MACHINE.

Application filed May 7, 1925. Serial No. 23,633.

My invention relates to improvements in beet topping machines of the type in which the topping means are carried by an auxiliary frame movably connected with the main frame of the machine, and in which a beet-engaging shoe is provided to vertically move the auxiliary frame to properly position the cutting blade with respect to the beets.

One object of the invention is to provide topping means of new and improved construction and mounted in a novel manner upon the auxiliary frame.

Another aim is to provide unique mounting and adjusting means for the beet-engaging shoe, so that it may be vertically adjusted with respect to the topping means or adjusted toward and from the latter, as occasion may demand.

A further aim is to provide an initial topping knife mounted in a novel manner in advance of the final topping means, said initial topping knife merely serving to remove the greater part of the foliage from the beet tops, while the other topping means effectively remove the remaining stubble.

A still further object of the invention is to provide a machine of the class set forth which is comparatively simple and inexpensive, yet will be very efficient and easy to operate.

With the foregoing in view, the invention resides in the novel subject matter herein-after described and claimed, the description being supplemented by the accompanying drawings.

Figure 1 is a top plan view.

Figure 2 is a side elevation partly broken away and in section.

Figure 3 is a perspective view of the auxiliary frame and associated parts.

Figure 4 is a detail transverse sectional view on line 4-4 of Fig. 1.

In the drawings above briefly described, the numeral 1 designates a main frame which preferably comprises side bars 2 connected at their rear ends by a cross bar 3 and having their front ends 4 bent inwardly toward each other, and suitably secured to a block 5 which is supported by a fork 6 having a front wheel 7, said fork having an upstanding spindle 8 journaled in the block 5 and secured to a tongue 9. Near their rear ends, the side bars 2 are provided with bearings 10 in which a rear axle 11 is rotatably mounted, said axle having appropriate driv-

ing wheels 12 at its ends, one or both of these wheels having ratchet connections (not shown) with the axle.

Loosely mounted upon the axle 11, is a gear 13 which may be connected with said axle by an appropriate clutch 13' which may well be controlled by a lever 14. This gear meshes with a pinion 15 on a short transverse shaft 16, the outer end of the latter being supported by a bearing 17 under one side 60 bar 2, while its other end is similarly supported by a bearing 18 carried by one of a pair of central longitudinal bars 19 whose ends are suitably mounted at the front and rear portions of the main frame. By means 65 of a sprocket chain 20 and suitable sprockets, the shaft 16 drives a second transverse shaft 21 disposed near the front end of the main frame and mounted in appropriate bearings 22 carried thereby, and by means 70 of a beveled gear 23 and pinion 24, the shaft 16 also drives a suitably mounted vertical shaft 25 whose lower end is provided with an eccentric 26. When the clutch 13' is thrown in, the gear 13 drives the pinion 15 and the 75 shaft 16, and the latter in turn drives the shafts 21 and 25, as will be readily understood.

Downwardly converging bars 27 and 28 are suitably connected at their upper ends 85 with the main frame, and at their lower ends, these bars carry a transverse rod 29 by means of which an auxiliary frame 30 is pivoted to the main frame. In the preferred form of construction, the frame 30 comprises 90 two side bars 31 which are provided at their rear ends with short upstanding standards 32, said standards and bars being relatively braced by appropriate plates 33. The two standards 32 are connected by upper and 95 lower transverse bars 34 and 35 which form the rear end of the auxiliary frame 30, said bars carrying upper and lower peripherally grooved rollers 36 and 37. A blade-carrying frame 38 of substantially arched form, is 100 disposed in a vertical transverse plane at the rear end of the frame 30 and is provided with a horizontal top bar 39 which is received for reciprocation between the upper and lower rollers 36 and 37, said frame being 105 connected by a transverse pitman 40 with the eccentric 26. A blade 41 is suitably connected with the legs of the frame 38, and said legs may be relatively sprung with respect to each other to either tighten the blade 41 for 110

use, or to permit detachment thereof, for instance when it should be sharpened. The means for springing the legs of the frame outwardly or inwardly preferably consist of a transverse bar 42 arranged between the legs as shown in Fig. 3 of the drawings and the respective ends of which have a right and left hand threaded engagement with said legs. On the projecting ends of the bar 42 nuts may be screwed. Draught links 43 are pivoted to and extend forwardly from the legs of the frame 38, and the front ends of these links may be connected with the frame 30 in any desired manner. In the present showing, one of the links is pivoted to an arm 44 projecting downwardly from a transverse shaft 44' which passes through openings in the side bars 31, and the other link 43 is pivoted to the lower end of a vertical bar 45 which is secured between its ends to the shaft 44'. I have shown the upper end of this bar 45 connected with one of the side bars 31 by a strap 46, so that said bar 45 and the shaft 44' are held against movement with respect to the frame 30.

At 47, a shoe is shown in front of the frame 38 and under the frame 30, and in the present showing, this shoe 47 is provided with a pair of longitudinally extending, plate-like arms 48 whose front ends are pivoted to a transverse rod 49. This rod is carried by crank arms 50 and 51 which project downwardly from a transverse rock shaft 52 carried by the front end portion of the auxiliary frame 30. The arm 50 is preferably formed by the lower end of a hand lever 53 which is secured to the shaft 52 for turning it, so as to move the shoe 47 forwardly or rearwardly, as occasion may demand. An appropriate pawl and rack 54 may well be provided for holding the lever 53 in adjusted position.

Two rods 55 rise from the shoe 47 at the rear portion of the frame 30 and pass slidably through guide ears 56 carried by a hand lever 57 which is fulcrumed at 58 to a short standard 59 rising from the bar 34. The upper ends of these rods are provided with nuts 60 providing shoulders which engage the upper sides of the ears 56, and the lower sides of these ears are in contact with coiled compression springs 61 which surround the rods 55. The lower ends of the springs 61 may either be connected to the rods 55, or may abut the upper side of the shoe 47. In either instance, when the lever 57 is swung in the proper direction to compress said springs, they will yieldably force the shoe 47 downwardly and will permit slight vertical yielding thereof during operation of the machine, whereas swinging of the lever 57 to the other direction will cause the ears 56 to engage the nuts 60, thus elevating the shoe 47 to the desired adjusted relation, with respect to the blade 41. For holding the le-

ver 57 in adjusted position, an appropriate pawl may be provided co-operable with a rack 62 secured to the standard 59.

Under the shaft 21, an initial topping knife 63 has been shown, said knife being carried by the lower end of a vertical shaft 64 whose upper end is provided with a pinion 65 meshing with a beveled gear 66 on the shaft 21. The shaft 64 has been shown rotatably mounted in an upper bearing 67 and a lower bearing 68. The bearing 67 is carried by the center of a transverse bar 69 whose ends are preferably bent rearwardly and secured to the bars 28. The bearing 68 is carried by a second transverse bar 70 whose ends are forwardly directed as at 71 and connected with the bars 28. The shaft 64 is provided with an appropriate shoulder or shoulders engaging its bearing means to hold it against descent, and it will be seen that by mounting this shaft in the manner shown, vertical adjustment of the auxiliary frame 30 will not affect said shaft or its driving connection with the shaft 21.

For raising and lowering the frame 30 as occasion may demand, I have shown a chain 72 whose lower end is connected with the shaft 44', while its upper end is connected with a crank arm 73 on a transverse rock shaft 74 suitably mounted at one side of the main frame, said shaft 74 having an appropriate operating lever 75 which may be locked in adjusted position by a pawl and rack 76.

Preferably used with the parts above described, are two disks 77 which straddle a row of beets to be topped, said disks being suitably mounted on a transverse bar 78, which is connected by links 79 with crank arms 80 and 81 on a transverse rock shaft 82 which is appropriately mounted on the front end of the main frame 1. The shaft 82 is provided with an upstanding arm 83 connected by a longitudinal link 84 with the lever 75, so that operation of this lever to raise the frame 31 and the beet topping means carried thereby, will also operate the shaft 82 to raise the disks 77. The bar 78 carrying the disks is preferably connected with the frame by inclined bars 85 secured to the former and pivoted to the latter.

During the operation of the machine, the initial topping knife 63 removes most of the foliage from the beet tops, the shoe 47 then engages the beets and as it rides over them, it swings the auxiliary frame 30 to properly position the knife or blade 41 with respect thereto, and this blade 41 which is being reciprocated by the frame 38 and pitman 40, effectively removes all remaining tops from the beets, leaving them in readiness to be dug.

Excellent results may be obtained from the general construction disclosed, and it is therefore preferably followed. However,

within the scope of the invention as claimed, modifications may of course be made.

I claim:

1. A beet topper comprising a main frame, an auxiliary frame pivoted at its front end to said main frame and having a transverse guideway at its rear end, a blade-carrying frame disposed vertically and mounted on said guideway for both reciprocating and swinging movements, a transverse beet topping blade carried by the lower portion of said blade-carrying frame, means for reciprocating the latter and draft links pivoted to said auxiliary frame and to the lower portion of said blade-carrying frame.

2. A beet topper comprising a main frame, an auxiliary frame pivoted at its front end to said main frame, upper and lower grooved rollers mounted on the rear end of said auxiliary frame, a vertically disposed blade-carrying frame disposed transversely at the rear end of the auxiliary frame and having a horizontal top bar received for reciprocation between said upper and lower rollers, a beet topping blade carried by said vertically disposed frame, means for reciprocating said vertically disposed frame, draught links pivoted to said vertically disposed frame and to said auxiliary frame, and means for effecting vertical movements of the auxiliary frame to dispose said blade in proper relation with the beets.

3. A beet topper comprising a main frame, an auxiliary frame pivoted at its front end to said main frame, beet topping means carried by the rear end of said auxiliary frame, a transverse rock shaft mounted near the front end of said auxiliary frame and having a pair of vertically projecting crank arms at its ends, a transverse rod carried by said crank arms, adjusting means for turning said shaft to forwardly or rearwardly move said rod, a longitudinally disposed beet engaging shoe connected at its front end to said rod, and means connecting the rear end of said shoe with the auxiliary frame, turning of the aforesaid shaft serving to vary the distance between the shoe and the beet topping means.

4. A beet topper comprising a main frame, an auxiliary frame pivoted at its front end to said main frame, beet topping means carried by the rear end of said auxiliary frame, a transverse rock shaft mounted near the front end of said auxiliary frame and having a pair of vertically projecting crank arms at its ends, a transverse rod carried by said crank arms, adjusting means for turning said shaft to forwardly or rearwardly move said rod, a longitudinally disposed beet engaging shoe connected at its front end to said rod, and vertically adjust-

able connecting means between the rear portion of said shoe and the rear end of the auxiliary frame, turning of the aforesaid shaft serving to vary the distance between the shoe and the beet topping means.

5. A beet topper comprising a main frame, an auxiliary frame pivoted at its front end to said main frame, beet topping means carried by the rear end of said auxiliary frame, a longitudinally disposed beet engaging shoe connected at its front end with said auxiliary frame, a rod rising from the rear portion of said shoe, a raising and lowering lever for said rod mounted on the rear end of the auxiliary frame and having a guide through which the upper end of the rod passes slidably, said rod having a shoulder engaging the upper side of said guide, and a coiled compression spring around said rod engaging the lower side of said guide.

6. A beet topper comprising a main frame having a transverse driven shaft, an auxiliary frame under said main frame having final topping means at its rear end, bars projecting downwardly from the main frame, means pivoting the front end of the auxiliary frame to said bars on an axis below said shaft, upper and lower transverse bars extending between the aforesaid bars and secured thereto, said transverse bars having central bearings, a vertical shaft rotatably mounted in said bearings, driving means connecting said vertical shaft with the above-named transverse shaft, and an initial topping knife carried by the lower end of said vertical shaft.

7. A beet topping machine comprising a main frame, beet topping means connected with said frame for vertical movements with respect thereto, a transverse rock shaft mounted on said frame for vertically moving said topping means, a pair of earth workers in advance of the topping means adapted to straddle a row of beets being topped, a transverse rock shaft connected with the earth workers for effecting vertical movement thereof, an operating connection between the two rock shafts for causing simultaneous turning thereof, and an operating lever for one of said rock shafts.

8. A beet topper comprising an arched frame, a topping blade extending between and connected to the lower ends of the legs of said frame, and means extending between said legs for springing them outwardly or inwardly, the top bar of the frame being straight and being adapted for engagement with a guideway.

In testimony whereof I have hereunto affixed my signature.

CHRISTIAN J. JENSEN.
